UNITED STATES PATENT OFFICE.

GEORGE A. RICK, OF WOODHAVEN, NEW YORK, ASSIGNOR TO A. G. SPALDING & BROS.,
OF NEW YORK, N. Y., A CORPORATION OF NEW JERSEY.

SHOULDER PAD.

Application filed September 3, 1925. Serial No. 54,308.

This invention relates to pads for the protection of the shoulder when carrying objects by means of a strap passing over the shoulder.

5 The important objects of the invention are the provision of a pad as above which is particularly adaptable for use with a caddy bag, and in which the pad is held in relation to the carrying strap against accidental displacement.

To this end the invention contemplates a pad having a resilient or soft under surface adapted to lie next to the shoulder of the one carrying the bag or other weighty object, to which is attached a leather backing. Overlying this backing is an upper leather member having lateral slots therein, the bag carrying strap being insertable through these slots so as to retain the pad on the strap. Means such as additional padding is provided in order to increase the frictional engagement of strap and pad so the latter will not become accidentally displaced thereon, which also serves to protect 25 the wearer's shoulder.

I have illustrated in the accompanying drawings a preferred form of the invention.

In these drawings:—

Figure 1 is a perspective view of one embodiment of my invention.

Fig. 2 is a plan view of a shoulder pad.

Fig. 3 is a sectional elevation along the line 3—3 of Fig. 2.

Fig. 4 is a transverse sectional view along the line 4—4 of Fig. 2.

Referring now to the embodiment shown, I have indicated a shield at 1 of fleece or other soft resilient material, having a backing 2 of leather or the like.

40 Overlying the backing 2 but of less width and length is a padding element 3 of any desired material.

Superimposed on the padding 3 and of

greater width and length is an upper leather 4 having three pairs of slots 5, 6, and 7, the individual slots of each pair being slightly spaced apart, as shown.

The fleece 1, backing 2 and upper leather are preferably stitched together around their periphery, as at 8.

50 The carrying strap of a caddy bag is shown at 9 passing through each pair of slots in the pad. It will be noted that the device is of sufficient length to extend over the shoulder of a wearer and slightly down the back 55 and front thereof. It should be of sufficient width to readily accommodate the straps and in addition provide enough extra width to protect the wearer's shoulder.

It is apparent that the carrying strap 60 lies between the upper leather 4 and the padding 3. Due to the fact that the padding 3 is slightly resilient, the strap 9 will be frictionally held in the pad and thus held 65 against accidental displacement. The padding 3 also assists in protecting the wearer's shoulder.

It will also be seen that the set of slots 6 prevents the strap from slipping laterally 70 of the shoulder at the top, while the pairs of slots 5 and 7 keep the strap and pad ends properly located.

I claim:

A shoulder pad comprising a fleece covered leather shield adapted to lie next to the 75 wearer's shoulder, padding material lying on top of the leather shield, an upper leather overlying the padding and stitched around its periphery to the leather shield, said upper leather having a series of slots therein, 80 through which a carrying strap may be threaded.

In testimony whereof, I affix my signature.

GEORGE A. RICK.
